UNITED STATES PATENT OFFICE.

HENRY B. CARY, OF LOS ANGELES, CALIFORNIA, ASSIGNOR OF ONE-HALF TO ARBA W. FROST, OF LOS ANGELES, CALIFORNIA.

WORD-COUNTING ATTACHMENT FOR TYPE-WRITING MACHINES.

1,207,275.

Specification of Letters Patent.

Patented Dec. 5, 1916.

Application filed May 28, 1914. Serial No. 841,514.

To all whom it may concern:

Be it known that I, HENRY BOUNDS CARY, a citizen of the United States, residing at the city of Los Angeles, county of Los Angeles, State of California, have invented new and useful Improvements in Word-Counting Attachments for Type-Writing Machines, of which the following is a specification.

- 10 My invention relates to improvements on the mechanism set forth and described in U. S. Patent No. 701,840, issued to me June 10, 1902, and the object of this invention is to simplify and improve the attachment disclosed in that patent. In that mechanism I arrange to operate the counting mechanism of the words by the spacer bar. In practice I find that it requires a full stroke of the spacer bar in order to count a word and does not require a full stroke of the spacer bar to space a word in writing. It frequently happens that an operator will space a word without a full stroke of the spacer bar and therefore will not count the word.
- 15 To obviate these defects is one of the objects of my present invention, and I do this by operating the counting mechanism as to the words by the lever which operates the type bar which prints the first letter of each word.

In my said patent I use two counters, one for words, and one for figures and characters counted as words. In my present improvement I use only one counter which is operated by two dogs which may be caused to move together or singly. The dog operated by striking the first letter of a word operates the counting mechanism and is held in an inoperative position thereafter until released by the operation of the spacer bar and while in its inoperative position it does not interfere with the operation of the other dog. In my former patent the cam bar was inside the rocking lever frame. In my present improvement said bar is outside the lever frame as it takes less power to operate it outside than inside said frame.

The above and other objects and the novel features of my invention will be apparent from the following description taken in connection with the drawings in which similar reference characters indicate the same parts in the several figures of the drawings in which:

Figure 1 is a side elevation of one of the base bars by means of which my attachment is secured to the frame of a typewriting machine, showing the parts carried by said base bar; Fig. 2 is a view of the parts shown in Fig. 1 in another position; Fig. 3 is a bottom plan view of the parts shown in Fig. 2; Fig. 4 is an edge elevation of the counter mechanism and its actuating levers viewed from the keyboard side of the machine; Fig. 5 is a side elevation of the parts shown in Fig. 4, from the machine side; Fig. 6 is a side elevation of the parts shown in Fig. 4 from the opposite side to that shown in Fig. 5; Fig. 7 is a section on the line 7—7 of Fig. 5; Fig. 8 is a bottom plan of the parts shown in Fig. 7; Fig. 9 is a bottom plan view of my attachment showing the same in position on a typewriting machine indicated in light lines; and Fig. 10 is a section on the line X—X of Fig. 9, looking in the direction of the arrows and with the parts in their upright position.

In the drawings 10 and 11 are base bars having holes 12 (see Figs. 7 and 8), extending therethrough to receive the screws 121 which connect the attachment to the bottom of the typewriting machine, as shown in Fig. 9. In the ends of the base bars nearest the keys of the machine are bearing blocks 14 which have a vertical movement in recesses in the base bars. These bearing blocks, one of which is shown in Figs. 2, 3 and 9, are adjusted vertically in the recesses in 10 and 11 by means of adjusting screws 16. By rotating the screws 16 the bearing blocks 14 may be raised or lowered independently of one another to raise or lower the fulcrum rod 17 which is carried by these blocks. One end of the fulcrum rod 17 is held in one block 14 by a set screw 18 and the other end of the rod passes entirely through the other block 14 and through the base bar 11 and a similar set screw holds this end of said rod in place.

The attachment illustrated in the drawings is used on an Underwood typewriter. A lever bar 19 is rockably mounted at one end on the fulcrum rod 17 and a screw 20 passes through an elongated slot 21 in the bar 19 and adjustably secures the latter to the inner side of the base bar 10. The other end of the bar 19 is bifurcated and straddles a part of the frame of the typewriter at 191,

see Fig. 9. A link bar 22 is provided with means at its upper end to connect it to the elevating bar of the shifting mechanism of the typewriter which shifts the type from lower to upper case printing position. The lower end of the link bar 22 carries a pin 23 which enters a slot 24 in the outer end of one element 25 of a compound lever which forms part of the actuating mechanism of cam shaft 26. The shaft 26 carries a series of cams, see Figs. 2, 3, 9 and 10. Figs. 1 and 2 show one of the cams 27 in two different operative positions. These cams are arranged so they will be struck and depressed by key levers carrying a figure or character counted as a word, thereby actuating the shaft 26 which carries the cams.

A stud 28 pivotally supports the element 25 on the bar 19 and the other end of the element 25 carries a pin 29 that enters the slot 30 between the ends of the other element 31 of said compound lever. The outer end of the element 31 is rockably mounted on the rod 17 and spaced from the bar 19 by a washer 32. The inner end of element 31 has an elongated slot 33 therein and the outer end of the crank 34 on the cam shaft 26 extends into this slot 33. The cam shaft is rockably mounted in the outer ends of the arms 261 of a swinging bail A, (see Figs. 9 and 10) the inner ends of said arms 261 being rockably mounted on the fulcrum rod 17 and the outer ends being connected by the cross pieces 262. Suitable collars 171 and 172 hold the bail A in place on the rod 17 and a coil spring 263 surrounds the rod 17 and has one end 264 bearing against the under sides of the cross pieces 262 to yieldingly press the bail upwardly and serves to restore the bail after the same has been depressed and released. This lower-to-upper-case adjustment of the cams provides for the counting of those upper case characters which count as words and for the elimination from the count of those characters which are not given the value of a word.

Referring to Figs. 5 and 6, the end of the shaft 26 opposite the crank 34 is mounted in a slot 35 in the inner member 36 of the cam shaft rocker arm which is pivotally mounted on the fulcrum rod 17. The outer member 37 of this rocker arm lies on the outside of base bar 11 and the two members 36 and 37 are connected by a body member 38 which passes across and below base bar 11.

The rocking frame B, see Fig. 9, consists of two side bars 391 pivoted between their ends, a front bar 392 depressible by the word spacing frame W to restore said frame to its initial position after the frame has been rocked by an alphabet key lever to actuate the counting mechanism to count a word. The backbar 39 of the rocking frame B is received in a notch at the free end of the inner member 40 of the rocking frame rocker arm

pivotedly mounted on the fulcrum rod 17. The outer member 41 of this last rocker arm lies on the outside of the base bar 11, but inside the outer member 37 of the cam shaft rocker arm. A body member 41^a (see Figs. 7 and 8) passes under the base bar 11 and connects members 40 and 41.

The bail A is rockably mounted on the rod 17 between the side members 391 but the free end of the bail extends outside of the frame B and the cam shaft 26 is mounted at the rear of the back bar 39, and hence less power is required to actuate the bail. The spring 393 carried by the fulcrum rod 17 frictionally engages one of the side bars 391 of the frame B and holds it either in its depressed or elevated positions.

A standard 42 has its lower end secured to the base bar 11 and is bent outwardly and upwardly and at its upper end carries a counting cylinder 42^a of any approved make. The counter has a shaft 43 which projects from the inside thereof and carries a disk 44 provided with a plurality of pins 45 equally spaced apart around the periphery of the disk. A detent arm 46 is pivotally mounted at the upper end of the standard 42 and has a bill 47 which is yieldingly held in engagement with the pins 45 by a spring 48. This bill permits the disk carrying the pins to rotate toward the pivot of the arm and prevents rotation thereof in the opposite direction.

An upwardly extending bar 50 (see Figs. 4, 5 and 6) is rockably mounted on the fulcrum rod 17 and adjustably connected by screw 49 to the outer member 37 of the cam shaft rocker arm. This adjustment is so that the upper end of the bar 50 can be positioned closer or farther from the counting cylinder 42^a. A bill-shaped dog 51 is rockably mounted at the upper end of the bar 50 and a spring 52 connected to the dog and bar holds the dog in such a position that when the bar 50 is rocked toward the counter, the end of the bill engages a pin 45 and rotates the disk 44 one tenth of a turn. When the bar is retracted the spring permits the bill to ride up over the next pin below it and move back out of the path of the pins.

An upwardly extending bar 54 is rockably mounted on the fulcrum rod 17 and its lower end is adjustably connected to the outer member 41 of the rocking frame rocker arm by a screw 53. This adjustment is such that the upper end of bar 54 can be positioned closer to or farther from the counter 42^a. A dog 55 is rockably mounted on the upper end of the bar 54 and has a nose 56 which projects to that side of the dog nearer to the pins of the counter and is angularly disposed to the body of the dog. The dog is held in such a position by the spring 57 that when the back bar 39 is struck and depressed by an alphabet key lever, and the

bar 54 is rocked, the body of the dog passes beyond the ends of the pins but the nose engages a pin and rotates the disk one tenth of a turn and then stops until retracted from 5 within the path of the pins when the spacing frame W strikes the front bar 392 and rocks the frame B to its initial position. This rocker frame may be so adjusted that it will remain in its alternate positions until acted 10 upon by either a proper key lever or the spacer frame, as the key levers after the first one struck, do not act upon the frame B, since its next operation must be effected by the operation of the spacer frame at the end 15 of a word. When bar 54 is retracted the spring 57 permits the nose to ride up over the next pin below it and move back out of the path of movement of the pins. It will be understood that the pins are held against 20 backward movement by the bill of the detent 46. A slotted guide plate 58 is secured to standard 42 and guides bars 50 and 54 in their movements toward and from the counter 42^a.

25 When the first letter of a word is struck the rocking frame B operates bar 54 to carry the nose of dog 55 into engagement with a pin on the disk 44 and to move disk 44 one tenth of a turn and then to pass within the 30 path of movement where the nose remains until the swinging frame B is released and retracted. The nose then returns to its normal position. When a numeral or sign that is counted as a word is struck the cam shaft 35 26 is operated and bar 50 moves dog 51 into engagement with a pin on the disk 44 and moves the disk 44 one tenth of a turn when the bar retracts the dog back to its normal position. It will thus be seen that the words 40 and the characters counted as words are all counted on the same counting device, thereby simplifying the mechanism of my before-mentioned patent. By the use of a compound lever in actuating the cam shaft so 45 little power is required that an operator can hardly detect from the touch of the keys when my attachment is on a machine.

In the mechanism described herein the 50 counting mechanism is constructed on the decimal system. If another counting mechanism should be used in which a different system would be used, the bars carrying the dogs would be applicable thereto by being so moved that a forward movement would turn 55 a counting disk of the counting mechanism to indicate one word counted. It will be seen that by this mechanism each word is counted when the first letter thereof is struck and that the nose of the dog which is actuated 60 by the alphabet key levers moves within the path of movement of the pins of the counting mechanism as it counts the word and is locked there until released by the spacer bar or frame W of the machine, and 65 that when in such position it does not inter-

fere with the dog actuated by the key levers of the machine carrying characters usually counted as words.

Referring to applicant's former patent No. 701,840, the rocking frame 12 in said patent performs the same functions as rocking frame B in the present invention, and the swinging bail 11 of said patent the same as bail A in the present application. The cams 33 of the patent corresponds to cams 75 27 of this application, and rock shaft 22 of the patent to shaft 26 of the present application. The shifting mechanism on left hand of counter of patent represented by elements marked 24, 25 and 26 is replaced by 80 elements 22, 31, 25 and 19, shown in this application. The transmission of motion of the rocking frame 12 to the register 35 by element 37 and motion of swinging bail 22 to register 36 by element 31 in above patent is accomplished in this application from frame B and bail A to a single counter 42^a by elements marked 35 and 54, and 35 and 50, respectively.

What I claim is:

1. In a word counting attachment for typewriting machines, the combination with a single register or counter, of means operable by the key levers of the alphabet characters to actuate said counter, and means 95 operable by the key levers of other keyboard characters that count as words to actuate said single counter.

2. In a word counting attachment for typewriting machines, the combination of a 100 single counter, of a rockable device operable by any one of the key levers of the alphabet characters to actuate said counter, and a second rockable device operable by the key levers of other keyboard characters counting 105 as words to actuate said single counter.

3. In a word counting attachment for typewriting machines, the combination with base bars attachable to the base of the machine, of a counting mechanism secured to 110 one of said bars, means operable by a portion of the key levers of the machine to actuate said counting mechanism, and other means operable by another portion of the key levers of the machine to actuate said 115 counting mechanism, said two means whether operated singly or together actuating said counting mechanism only a step at a time.

4. In a word counting attachment for typewriting machines, the combination with counting mechanism, of means operable by a portion of the key levers of the writing machine to actuate said counting mechanism, said means comprising a series of 120 cams engageable by said levers, a rockable cam shaft carrying said cams, a crank arm connected to said cam shaft, a compound lever connected to said crank arm, and a link connected to the compound lever, said 125

90

95

100

105

110

115

120

link being attachable to the lower-to-upper-case shifting mechanism of the machine whereby said cams are adjusted when the shifting mechanism is operated.

5. In a word counting attachment for typewriting machines, the combination with counting mechanism, of means operable by a portion of the key levers of the writing machine to actuate said counting mechanism, said means comprising a series of cams engageable by said lever, a rockable cam shaft carrying said cams, a crank arm connected to said cam shaft, a compound lever comprising two elements connected together by a pin-and-slot connection, one of the elements being pivoted at one end and having its free end connected to said crank arm by a pin-and-slot connection, the other of said elements being pivoted between its ends, and a link connected to one end of said other element, said link being attachable to the lower-to-upper-case shifting mechanism of the machine whereby said cams are adjusted when the shifting mechanism is operated.

6. In a word counting attachment for typewriting machines, the combination with a single counter, of means for actuating said counter comprising devices independently operable by different sets of key levers of the machine, and means for adjusting said counter and devices with respect to each other.

7. In a word counting machine for typewriting machines, the combination of base bars adapted for attachment to a typewriting machine, bearing blocks, a fulcrum rod carried by said blocks, means for securing said blocks to said bars and also for adjusting said blocks and the rod carried thereby, counting mechanism, and means mounted on said rod for actuating said counting mechanism.

8. In a word counting attachment for typewriting machines, the combination with counting mechanism, of two independent actuating means therefor operable by different groups of key levers of the machine, and means for adjusting the positions of both of said actuating means with respect to said counting mechanism.

9. In a word counting attachment for typewriting machines, the combination with base bars attachable to the frame of a writing machine, a fulcrum rod adjustably mounted in said base bars, a compound lever comprising two pivoted elements, the first of which is connected near its end to a point between the ends of the second element which is pivoted on said fulcrum rod, a cam shaft carrying a plurality of cams operable by a set of key levers of said machine, a crank arm on said cam shaft connected to the free end of said second element, a link connected to the free end of the first element

and attachable to a part of the mechanism for machine shifting from upper case to lower case and vice versa, a device carried by said rod and operable by another set of key levers of said machine, and counting mechanism adapted to be actuated by said cams and said device.

10. In a word counting attachment for typewriters, the combination of base bars adapted for attachment to the frame of the machine, a fulcrum rod connected to said base bars, two independent rocking frames mounted on said fulcrum rod and operable by different sets of key levers of said machine, a standard secured to one of said base bars, a counting device mounted on said standard, and independent means, one connected to one rocking frame and the other connected to the other rocking frame for actuating the counting device.

11. In a word counting attachment for typewriting machines, the combination with a counting device having a rotatable shaft, of a disk mounted on said shaft and having ten equally spaced projections on a face thereof, rockably mounted dogs and means operable by different sets of key levers of the machine to cause said dogs to engage a projection and turn said disk one tenth of a turn.

12. In a word counting attachment for typewriting machines, the combination with a single counting device having a rotatable shaft, of a disk mounted on said shaft and having ten equally spaced pins projecting from the face thereof, a bar, a hookbill dog mounted on said bar, means operable by a key lever of the machine to cause said bar to move said dog to engage a pin and turn said disk one tenth of a turn, a second bar, a second dog mounted on said second bar and having an inclined nose projecting from one side thereof, means operable by a lever of the machine to cause said second bar to move the nose of said second dog to engage a pin and turn said disk one tenth of a turn, and means to prevent said disk from turning backward.

13. In a word counting attachment for typewriting machines, the combination with a counting mechanism, of means for actuating said mechanism to count words, a portion of the key levers of the typewriting machine being adapted to operate said actuating means to cause the registration of a word by said counting mechanism and the word-spacing device being adapted to restore said actuating means to its normal position.

14. In a word counting attachment for typewriting machines, the combination with a counting mechanism, of means comprising a rockable frame for actuating said mechanism, the first struck alphabet key lever of a word being adapted to rock said

frame to cause it to operate said counting mechanism to count a word, and the word-spacing device, when struck, being adapted to rock said frame and restore it to its initial position.

15. In a word counting attachment for typewriting machines, the combination with a counting mechanism, of a frame operable by the key levers of the alphabet characters, to actuate said counting mechanism, a cam shaft located outside the outline of said frame and adapted when actuated to operate said counting mechanism, and cams mounted on said cam shaft and operable by 10 the key levers of other key board characters which count as words.

16. In a word counting attachment for typewriting machines, the combination with a counting mechanism, of a fulcrum rod, 15 a frame pivoted on said fulcrum rod and

operable by the key levers of the alphabet characters to actuate said counting mechanism, a second frame pivoted on said fulcrum rod within the first frame and extending outside of the latter, a cam shaft mounted in said outside part of the second frame, cams mounted on said cam shaft and engageable by the key levers of other key board characters which count as words, and means connected to the cam shaft and attachable to the shifting mechanism of the typewriting machine to adjust the cams for upper and lower case characters.

In witness that I claim the foregoing I have hereunto subscribed my name this 7th 20 day of May, 1914.

HENRY B. CARY.
